UNITED STATES PATENT OFFICE

2,585,160

BRICKLAYER'S GUIDE

John R. Munn, Silver Creek, Minn.

Application April 29, 1949, Serial No. 90,471

1 Claim. (Cl. 33—85)

1

The present invention relates to bricklayer's guides and it consists in the combinations, constructions and arrangements of parts herein described and claimed.

Generally there is provided a device for holding the conventional guide lines used in the laying of bricks. Two of the devices are utilized to hold between them the guide line and each of the devices is provided with an L-shaped body which is adapted to grip the corner portion of a wall, the tension of the guide line serving to hold the members in position. Novel means is provided for releasably fastening the ends of the guide lines in each of the members utilized and novel means is provided for tensioning the guide holding means. Means is also provided for insuring the device against slippage when once placed in position.

It is accordingly an object of the invention to provide a device of the character set forth which is simple in construction, inexpensive to manufacture and yet effective and efficient in use.

A further object of the invention is to provide a device of the character set forth which will eliminate the necessity of providing nails for holding a guide line and also for eliminating other crude methods heretofore employed for this purpose.

Another object of the invention is the provision of novel releasable means for holding rigidly the end of a guide line in a device of the character set forth.

Other and further objects of the invention will become apparent from a reading of the following specification taken in conjunction with the drawing, in which:

Figure 1 is a perspective view of an embodiment of the invention shown in use upon the corner of a brick wall,

Figure 2 is an enlarged plan view of the device shown in Figure 1,

Figure 3 is a fragmentary further enlarged central sectional view of the device, and

Figure 4 is a sectional view taken along line 4—4 of Figure 3.

Referring more particularly to the drawing, there is shown therein a bricklayer's guide comprising an L-shaped frame having a relatively short leg 10 and a relatively longer leg 11 and having a centrally disposed opening 12 formed therein at the point of juncture between the legs 10 and 11.

The free end of the leg 10 is provided with an turned pointed foot 13 and the free end of the

2

arm 11 is provided with a like inturned pointed foot 14 which has centrally disposed therein a notch 15.

5 A handle 16 is affixed to the arm 11 by means of rivets 17 or the like. Through that part of the handle which is adjacent the point of juncture of the arms 10 and 11 extends a carriage bolt 18 having a squared portion 19 which fits an opening 20 formed in the handle 16. Slidably mounted upon the squared portion 19 is a dished washer 21 having its convex face presented toward the handle 16.

10 A nut 22 is threaded upon the outer end of the carriage bolt 18 and a washer 23 is mounted upon the bolt inwardly of the nut and a compression spring 24 surrounds the bolt 18 and is adapted to bear against the concave surface of the washer 21 and against the inner face of the washer 23. A guide line 25 has its free end wound about 15 the squared portion 19 of the bolt 18 between the outer side of the handle 16 and the convex face of the washer 21, as shown at 26, and extends thence through the opening 12 and thence through the notch 15 to a twin of the device now 20 described.

25 In use, it will be apparent that two of the devices shown and described herein will be utilized to hold taut the guide line 25 and that each of the devices may be quickly and easily mounted 30 upon the corner of a wall such as is shown, for example, at 27 in Figure 1, and that when so mounted the free ends of the line 25 will be pulled through the notch 15 and opening 12 and then wound upon the carriage bolt and that 35 thereafter the washer 21 will hold the same in position. When this is done the line 25 will hold the two devices together upon the corners of the wall which is under construction and that the pointed feet 13 and 14 will prevent the devices 40 from slipping downwardly upon the wall. It will also be apparent that a proper tension may be maintained upon the washer 21 by adjusting the position of the nut 22 upon the carriage bolt 18.

45 While but one form of the invention has been shown and described herein, it will be readily apparent to those skilled in the art that many minor modifications may be made without departing from the spirit of the invention or the scope of the appended claim.

50 What is claimed is:

A device of the character described comprising an L-shaped body having a centrally disposed opening at the juncture of its arms, a handle attached to one of said arms, an inturned tooth formed integrally at the outer end of each arm,

said tooth for the longer arm having a centrally disposed notch therein, a bolt non-revolubly mounted in said handle and having its threaded end extending outwardly therefrom, a yieldable line holder mounted on said bolt and means for regulating the tension of said yieldable line holder, said means including a dish-shaped washer slidably mounted upon said bolt and having its convex face presented toward the handle, a nut threadably mounted on said bolt, a flat washer upon said bolt inwardly of said nut and a compression spring surrounding said bolt and bearing against both washers.
